Article of furniture, as shown and described, consisting of a pedestal frame for the drawers or other members, described below, comprises a bottom 1, a back 2, side members 3 and 4 and top member 5 all suitably held together. Side member 4 has ledges 6, preferably integral with the side member, and the tops of these are spaced at equal distances apart. Side member 3 has similar ledges not necessary to be shown. Suitable drawers or slides are used to move in and out on said ledges. One of these drawers is shown fully in Figure 3 and comprises a base 7 and four upright side pieces 8, 9, 10 and 11 suitably joined. The

base 7 is extended outside of side 11 at 12 to form a projection in the nature of a key to ride on one of the ledges 6 in side 3. An extension like 12 (not shown) projecting from side 9 will ride in one of the ledges 6 in side 4. The height of the drawer is slightly less than the distance from the top of one ledge to the top of the next ledge above or is slightly less than a multiple of said distance, such distances being equal for all ledges. In Figure 1 I show, by way of illustration, a slide 13, a drawer 14 and also a drawer 15, the space in the drawing between drawers 14 and 15 being left open to show interior construction, it being understood that this space would normally be filled by other drawers or slides, as in Figure 2, 15 it being further understood that the drawer of Figure 3 may be used in the pedestal shown in Figure 1, the point being that the entire space between bottom 1 and top 5 may be filled by a plurality of drawers or slides which may differ 20 from one another in height so long as the sum of their heights fills said space, although if desired one or more slides may be used as a shelf or shelves providing open space for storage. With my arrangement the drawers and slides may 25 be interchangeable as to their relative vertical arrangement, so that, for example, the seven sliding elements in Figure 2 may be rearranged, as desired. Moreover, a greater or less number could be used to fill the space between bottom 1 30 and top 5 so long as each of them is, in height, equal to, or a multiple of, the distance from the top of one ledge to the top of the next and in case said space is to be substantially filled the sum of the heights of all the members will be 35 substantially equal to said space.

It will be understood that the side pieces 9, 10 and 11 may be as high, but must not be higher, than the height of the front side piece 8 so that no element will ride on the movable element below it. To provide additional top surface the leaf 16, hinged at 17, to top 5 may be swung back into the dotted position of Figure 2. If desired, any additional support, other than hinges 17, may be 45 provided. Hinged at 18 to top 5 is a shelf 19 to provide additional table top surface. This shelf 19 may be held in elevated position by suitable folding brackets connecting shelf 19 and side 4, but I 50 prefer to support shelf 19 by a leg pivoted to the outer end of shelf 19 at 20 to obtain greater stability. When the distance from the upper side of top 5 to the floor is greater than the length of the shelf 19 it is highly important that the support 55

UNITED STATES PATENT OFFICE

ARTICLE OF FURNITURE

Andrew D. Fuller, Boston, Mass.

Application July 8, 1933, Serial No. 679,558

1 Claim. (Cl. 311—52)

The principal object of my invention is to provide an article of furniture to be used as a table for dining or other domestic uses or as a card table or otherwise or as a work table or work bench for a great variety of uses in combination with a pedestal or cabinet for storage of implements, materials, books or other things.

A feature of my invention is a pedestal or cabinet so constructed as to provide ready interchangeability, as desired, of the containers or other sliding elements within the pedestal.

Another feature is that I extend the container or other sliding elements to ride on ledges in the pedestal or cabinet.

Another feature is a supporting leg comprising two relatively movable members, preferably telescopic, to provide support for a leaf hinged to a pedestal or cabinet, especially when the length of the leaf is less than the height from the floor to the under side of the leaf when the latter is raised, it being understood that said two relatively movable members are carried by said hinged leaf.

Other features are described below.

In the drawings

Figure 1 is a perspective of an article of furniture embodying my invention;

Figure 2 is a perspective of the pedestal shown in Figure 1 combined with members for extending the top surface and with a supporting leg fully described below; and

Figure 3 is a perspective showing the structure of a drawer.

Figure 4 is a longitudinal vertical section through the shelf, leg and support, said section being taken of the device, set up as shown in Figure 1;

Figure 5 is a transverse vertical section through the leg and shelf, said section being taken of the device set up as shown in Figure 1; and

Figure 6 is a longitudinal vertical section of the device when completely collapsed.

A pedestal frame for the drawers or other members, described below, comprises a bottom 1, a back 2, side members 3 and 4 and top member 5 all suitably held together. Side member 4 has ledges 6, preferably integral with the side member, and the tops of these are spaced at equal distances apart. Side member 3 has similar ledges not necessary to be shown. Suitable drawers or slides are used to move in and out on said ledges. One of these drawers is shown fully in Figure 3 and comprises a base 7 and four upright side pieces 8, 9, 10 and 11 suitably joined. The

ing leg be capable of extension to correspond with said distance so that the leg may be folded against the under side of shelf 19 and the latter and the leg may be swung down on hinge 18 so as, when 5 not in use, to lie substantially parallel with side 4. When the shelf 19 is raised to horizontal position the leg will hang down in vertical position but will not reach the floor if the distance from the shelf (in such horizontal position) to the floor 10 is greater than the length of the shelf 19 and consequently it is made extensible. One form of such extensibility is shown in Figure 2 in which two telescoping members are used, the upper one comprising two side portions 21 and 22 held in proper spaced position by block 23, side portion 22 being interiorly grooved to receive key 24 and side portion 21 being interiorly grooved to receive key 25, both of these keys being integral with the other telescoping member 26, the latter having a 15 suitably formed foot 27 to engage the floor. The telescoping members are held in the extended position shown in Figure 2 by spring bolt 28 mounted through member 21 and engaging in a hole (not shown) in member 26, this hole being like 20 hole 29 in member 26, which hole engages spring bolt 28, when the telescoping members are collapsed, to hold them in collapsed position as when they lie alongside wall 4 as well as until the shelf 25 is fully raised, at which time spring bolt 28 is released from hole 29 so that member 26 may drop to the floor and the spring bolt 28 may then 30 engage in the hole (not shown) in member 26. The spring bolt engaging in one or the other of the two holes in member 26 prevents all accidental separation of the two telescoping members. Any suitable folding bracket, such as 30, connects 35 either member 21 or 22 with shelf 19 to hold the leg in vertical position.

I provide a block 31 fixed to shelf 19 and extending across the latter and being spaced from the side portions 21 and 22 and connecting block 23 of the upper telescoping member, said block being provided with a finger recess 32, the purpose of this feature being to prevent pinching of the 40 fingers while the shelf 19 is being raised to horizontal position and while, consequently, the leg is swinging with relation to shelf 19, this guarding of the fingers being an important advantage from the practical standpoint.

50 Hinged to shelf 19 at 33 is leaf 34 which may be swung through 180° backward into the dotted line position of Figure 2 when it is desired to have additional table top surface at the rear of shelf 19. It will be understood leaf 16 may occupy 55 either its full line or dotted position independently of the position of leaf 34 and the latter may occupy its full line or dotted line position independently of leaf 16 or, if desired, leaves 16 and 34 may be turned together in fixed relation to 60 their dotted line positions when they are held in fixed relation by bolt 35 engaging in recess 36.

The shelf 19 may be hinged to top 5 at the edge opposite to the edge to which it is shown hinged in Figure 2 or it may be hinged at the rear of top 65 5 with the leaves 16 and 34 hinged appropriately for such other locations.

The bolt 35 not only provides for simultaneous swinging of leaves 16 and 34 but aligns those leaves with relation to each other if both are closed as in full lines, or both are open as in dotted lines.

5 For one living in restricted quarters, as many women do, and obliged to go out for or prepare and consume meals under hit or miss conditions my article of furniture gives a new zest to life from its very convenience of use, orderly storage 10 compartments and compactness when not in use. It can be moved about the room easily, placed in advantageous position for work or for play and then folded and returned to its space-saving position when, with the top raised and folded back 15 against the wall, it makes a pleasant addition to the room.

Without such accommodation the constant getting up and down to fetch something lacking 20 in the usual set up, as enough sugar, salt, silver or what not, becomes sufficient mental strain to prevent proper nourishment being consumed.

With this table I have everything at hand for the ordinary use to which the table is to be put. 25 If it is for domestic use, such as cooking and eating, then the heights of drawers are selected accordingly and prove to be adequate in size and depth for the needs of one or more persons. By following the prescribed plan of orderly arrangement enough linen, silver, glass, dishes, utensils 30 and supplies, each in its appointed place, can be stored in the drawers to meet the needs of one or two.

In a similar way the table is adaptable to many 35 other locations and uses. As a work table or bench the ability to change easily the vertical sequence of the drawers enables each user to place at the top or most convenient position for use the size of drawer, whether small or large, for tools or supplies most in use and yet be able to change 40 again whenever the work or tools change.

The form of supports, whether a drawer, a 45 cupboard or a slide as a shelf, often determines the size of the article to be stored. In this table the drawer or cupboard or shelf space can be made to fit any article within the total storage height. The whole table can be folded easily against the drawer casing, slipped into a carton jacket and taken to a new location or mailed 50 there by parcel post.

All the parts, or any part, of my article of furniture may be made of wood or metal or other suitable material.

What I claim is:

An article of furniture comprising a support; 55 a shelf pivotally connected to said support; a leaf pivotally connected to the top of the support on an axis which is at a right angle to the axis upon which the shelf is pivoted; a leaf pivotally connected to the shelf on an axis which is at a right angle to the axis upon which the shelf is pivoted; and means to lock the leaves together for simultaneous movement thereof and for alignment thereof.

ANDREW D. FULLER. 65
